UNITED STATES PATENT OFFICE.

ADOLPH F. SCHRAMM, OF COLUMBUS, OHIO, ASSIGNOR OF ONE-HALF TO SEYMOUR H. FISHER, OF COLUMBUS, OHIO.

AUTOMOBILE-SEAT.

1,332,957.

Specification of Letters Patent.

Patented Mar. 9, 1920.

Application filed October 23, 1919. Serial No. 332,699.

To all whom it may concern:

Be it known that I, ADOLPH F. SCHRAMM, a citizen of the United States, residing at Columbus, in the county of Franklin and State 5 of Ohio, have invented a certain new and useful Improvement in Automobile-Seats, of which the following is a specification.

The particular object of this invention is to provide a back for an automobile seat that 10 may be adjusted to stand somewhat forward of its normal position. Such a back is particularly desirable for the use of drivers who are undersized or whose legs are short and with whom it is therefore necessary to 15 sit so far forward on the ordinary seat as to preclude the practicability of resting or bracing their backs while operating the foot levers or driving the vehicle.

The invention is embodied in the construction herein shown and described, the features of novelty being finally claimed.

In the accompanying drawing—

Figure 1 is a vertical section through the back taken on a plane just forward of the line where the adjusting mechanism is located, the farther portion of the seat, back and arms being indicated in perspective by broken lines. In this view the back is shown in its adjusted or forward position.

Fig. 2 is a similar view (except that the perspective lines are omitted) showing the back in normal position.

Fig. 3 is a section on the line III—III Fig. 2, looking to the left, the adjusting 35 mechanism being shown in edge view.

Fig. 4 is a detail view of the linking means.

Secured to the permanent rear wall 5 of the back is an upper bracket 6 and lower bracket 7, said brackets having in their rear portions similar slots 6^a and 7^a respectively terminating in pin seats. The forward portion of the upper bracket has an upwardly opening notch 6^b while the forward portion 45 of the lower bracket has a horizontally opening notch 7^b.

Hingedly connecting an end wall 8 of the upholstered back 9 with the respective brackets are short links 10 and 11, the lower 50 link 11 being slotted at 11^a to slide on its hinging pin 12 in the bracket 7.

The two short links 10 and 11 are connected by a longer link 13 that is hinged at its end to said links 10 and 11 by pins 14 55 and 15, said pins engaging the notches 6^b

and 7^a respectively when the back is in normal position and the notches 6^b and 7^a respectively in forward position. The long link 13 keeps the short links in proper operative relation to each other and the back. 60

The slot 11^a of the lower short link 11 permits the horizontal movement of the pin 15 into and out of the notch 7^b. When, in the forward position of the back, said pin 15 is engaged with said notch 7^b the back is 65 latched from upward movement. The lower portion of the back has secured to it a pull strap 16 by means of which the back can be manipulated. The back is adjusted to forward position by pulling slightly upward 70 and forward upon the strap 16 to withdraw the pins 14 and 15 from the notches 6^a and 7^a until the pins 14 and 15 have entered the notches 6^b and 7^b a rearward push at the lower portion of the back being employed to 75 send the pin 15 into the notch 7^b. To adjust the back from forward to normal or rear position the operation is simply reversed.

I have shown and described herein but one set of means for hinging the back to 80 the permanent wall. In practice it will be advisable to provide the back with duplicates of the means described, each substantially identical with the other in construction and in parallel arrangement. 85

The forms of the parts can be changed without departing from the gist of the invention as claimed.

What I claim is:

1. In a seat, the combination with a movable back and a stationary back, of upper and lower links connecting the two backs, and means for latching the movable back from vertical movement in its forward position. 90

2. In a seat, the combination with a movable back and a stationary back, of upper and lower links connecting the two backs, a third link connecting the first mentioned links and means for latching the movable back from vertical movement in its forward position. 95

3. In a seat, the combination with a stationary back wall and brackets thereon and a movable back, of means hinging the movable back to said brackets permitting forward adjustment of the back and means for latching the back from vertical movement when the movable back is adjusted to forward position. 105

4. In a seat, the combination with a stationary back wall and brackets thereon and a movable back, said brackets provided with rear and forward notches, links hinging the movable back to said brackets and pins carried by said links to engage said notches.
5. In a seat, the combination with a stationary back wall and upper and lower brackets thereon and a movable back, said brackets each provided with rear and forward notches, the upper of said notches opening upwardly and the lower of said notches opening substantially horizontally, links hinging the movable back to said brackets, and pins carried by said links to engage said notches.
6. In a seat, the combination with a permanent back wall and brackets thereon and a movable back, said brackets provided with rear and forward notches, links hinging the movable back to said brackets, a link connecting said links and pins carried by the first mentioned links to engage said notches.
7. In a seat, the combination with a stationary back wall and upper and lower brackets thereon and a movable back, said brackets each provided with rear and forward notches, the forward notch of the upper bracket opening upwardly and the forward notch of the lower bracket opening substantially horizontally, links hinging the movable back to said brackets and pins carried by said first mentioned links to engage said notches, the lower of said links provided with a slot to permit longitudinal movement on its hinging pin.
8. In a seat, the combination with a stationary back wall and upper and lower brackets thereon and movable back, said brackets each provided with rear and forward notches, the forward notch of the upper bracket opening upwardly and the forward notch of the lower bracket opening substantially horizontally, links hinging the movable back to said brackets, pins carried by said first mentioned links to engage said notches, the lower of said links provided with a slot to permit longitudinal movement on its hinging pin and a link connecting said first mentioned links.
9. In a seat, hinging means for connecting a movable back with a stationary back including a pair of brackets on one of said backs, one of said brackets provided with a forward and a rear seat, a pair of links hinged to said brackets, a link connecting said links and means carried by one of said links for alternately engaging one of said seats.
10. In a seat, a hinging means for connecting a movable back with a stationary back including a pair of brackets, a pair of links hinged to said brackets, a link connecting said first mentioned links, the lower of said first mentioned links being longitudinally movable at its hinged connection and means carried by one of said links for latching the movable back from vertical movement in its forward position.

ADOLPH F. SCHRAMM.
